UNITED STATES PATENT OFFICE.

AARON SLUTSKY, OF NEW YORK, N. Y.

SOUND-REPRODUCING APPARATUS.

Application filed October 15, 1926. Serial No. 141,685.

This invention relates to sound-reproducing apparatus more particularly intended for use in connection with phonographs and has for its object to provide means for reproducing sounds which will be simple and cheap in construction and yet at the same time be free from harsh metallic sounds and produce a louder, purer and clearer tone than heretofore.

With the above and other objects in view the invention consists in a combined sound-box or "reproducer" and horn constructed, in compact form, of strawboard, cardboard or similar material and impregnated with lacquer or shellac which I have found increases the tonal qualities of the material and gives a really pleasing reproduction.

In the accompanying drawings:—

Figure 1 is a front view of one embodiment of the apparatus constructed according to the present invention.

Fig. 2 is an end view thereof, and,

Fig. 3 is a similar view to Figure 1 but showing the sound-box in section and a horn of modified shape.

Referring more particularly to Fig. 3 of the drawings the sound-box according to the present invention is built-up from a plurality of layers of cardboard, strawboard or like material interposed between which is the usual diaphragm 6 of mica or other suitable material, the external shape of the particular sound-box illustrated being hexagonal.

On either side of the diaphragm 6 are provided the usual protecting and retaining rings 8 of rubber for the diaphragm.

Around the diaphragm 6 and rings 8 are disposed the various layers of cardboard or the like which are used according to the present invention to build up the sound-box, these comprising:—

(a) Several layers 10 disposed outside or beyond the diaphragm 6 and rings 8, these layers being provided with large centrally-disposed circular openings to receive said diaphragm and rings;

(b) Two layers 12 and 14 disposed one on either side of the layers 10 and having smaller central openings 16, the greater amount of material left serving to hold by compression the diaphragm and rings firmly in place as will be clear from an inspection of Fig. 3.

(c) A layer 18 outside of the layer 12 provided with a smaller central opening 22 to which layer is secured in any suitable man-

ner a socket 24 by which the sound-box can be connected to the usual tone arm 25 of a phonograph or be otherwise supported in correct relation to a record to be played.

(d) A layer 20 having a small central square opening 26 adapted to receive and hold a further and preferably squared socket 28 which in turn is adapted to receive and hold, as by a screw 30, a small horn 32 which may be used supplemental to the usual horn with which a machine is provided or independent thereof. However, the horn 32 may be dispensed with, the socket 28 acting in such case in lieu thereof.

The various layers of material forming the sound-box above described are suitably glued or cemented one to the other and are preferably bound on the outside by layers of paper 34, or the exposed surfaces of the cardboard layers before the paper is applied may be impregnated with shellac, for the purposes and with the objects hereinbefore mentioned.

A suitable lacquer for the purpose is one consisting of a solution of about 20 per cent amyl acetate and about 80 per cent acetone solution of nitrocellulose, which on drying forms a layer of cellulose material.

This solution prevents the box from absorbing any sound as all the pores thereof are closed thereby and the entire sounds reproduced are therefore conveyed from the box through the horn. It also hardens the entire box to such an extent that it takes the place of a metal box in its hardness.

It will be observed that the outer layers 18 and 20 practically completely shield the diaphragm 6.

The horn 32 is also made of one or more layers of cardboard suitably shaped, covered with paper and impregnated with lacquer in the same manner as the sound-box.

To the diaphragm 6 is connected, as by a screw 36, the stylus bar 38 which at its outer end merges into the transverse plate or bar 40 from the centre of which depends the stylus holder 42. It will be noted that the layer 20 is provided with an elongated slot 52 to permit the rod 38 to reach the diaphragm 6.

About the lowermost part of the sound-box is disposed a U-shaped metal bracket 44 secured in place by screws 46 which pass through holes tapped therethrough and through the various layers of material forming the sound-box. These screws also hold

in place the springs 48 which in turn fulcrum the bar 40 against the downwardly-projecting pins or knife-edges 50 with which the bracket 44 is provided.

5. What I claim is:—

1. Sound-reproducing apparatus comprising a diaphragm, a plurality of annular layers of cardboard enclosing said diaphragm and forming a sound box, said layers being 10 cemented one to the other and the sound box being lacquered on its exposed surfaces, a horn carried by one of the said layers of cardboard and means for conveying vibrations to said diaphragm.
- 15 2. Sound-reproducing apparatus for phonographs comprising a diaphragm, a plurality of layers of cardboard enclosing said diaphragm and forming a sound box, said layers being cemented together and the 20 sound box being lacquered on its exposed surfaces, means for conveying vibrations to said diaphragm, a horn formed of lacquered cardboard, means carried by one of the outer layers enclosing the diaphragm for supporting said horn, and means carried by the 25 other outer layer enclosing the diaphragm for connecting the apparatus to a phonograph.
3. A sound-box for phonographs comprising a diaphragm, positioning rings encircling said diaphragm circumferentially at either side thereof, a layer of cardboard on the outer side of each of said rings and pressing thereon to retain the same and the 35 diaphragm in position, an outer layer of cardboard on the outer side of each of said last-mentioned layers, all of the layers hereinbefore mentioned being cemented to form an integral sound box and the exposed surfaces of the sound box being lacquered, a horn carried by one of the said outer layers of cardboard, means for conveying vibrations to the diaphragm, and means for connecting the sound-box to a phonograph.
- 45 4. A sound-box for phonographs comprising a diaphragm, suspension rings disposed circumferentially on either side thereof, a plurality of layers of cardboard cemented together enclosing and retaining said diaphragm and rings and of disc-like forma-

tion with centrally-disposed openings of various sizes, a horn connected to and carried by one of the said layers of cardboard, means for conveying vibrations to the diaphragm, and means for connecting the sound-box to a phonograph.

5. A sound-box for phonographs comprising a diaphragm, suspension rings disposed circumferentially on either side thereof, a plurality of layers of cardboard cemented together enclosing and retaining said diaphragm and rings and of disc-like formation with centrally-disposed openings of various sizes, means for conveying vibrations to the diaphragm, means for connecting the sound-box to a phonograph mounted at one side of said box and a horn carried by the layer of cardboard at the opposite side of said sound-box.

6. A sound-box for phonographs comprising a diaphragm, suspension rings disposed circumferentially on either side thereof, a plurality of layers of cardboard cemented together enclosing and retaining said diaphragm and rings and of disc-like formation with centrally-disposed openings of various sizes, means for conveying vibrations to the diaphragm, means for connecting the sound-box to a phonograph mounted at one side of said box and a horn, also of cardboard and lacquered, carried by the layer of cardboard at the opposite side of said sound-box.

7. A sound-box for phonographs comprising a diaphragm, a plurality of layers of cardboard enclosing said diaphragm, said layers being cemented one to the other, a horn secured to and carried by one of said layers of cardboard, an elongated slot in one of said layers, a stylus bar connected to said diaphragm and passing through said elongated slot, a transverse member formed integral with said bar at its outer end, a stylus holder depending from said member, a U-shaped bracket disposed about the lowermost part of said sound-box, and carrying fulcrum pins and springs for said transverse member.

In testimony whereof I have signed my name to this specification.

AARON SLUTSKY.
